Primary Examiner — Ian Simmons*Assistant Examiner* — Shannon Morgan(74) *Attorney, Agent, or Firm* — Janeen Vilven; Peacock Myers, P.C.(57) **CLAIM**

The ornamental design for a skirt, as shown and described.

DESCRIPTION

FIG. 1 is a perspective view of a skirt with attachment loops showing our new design;
FIG. 2 is a front view thereof;

FIG. 3 is a back view thereof;

FIG. 4 is a left side view thereof;

FIG. 5 is a right side view thereof;

FIG. 6 is a top plan view thereof; and,

FIG. 7 is a bottom plan view thereof.

The broken lines shown in FIGS. 1-7 represent portions of the skirt that form no part of the claimed design.

1 Claim, 4 Drawing Sheets(56)
